UNITED STATES PATENT OFFICE.

HOWARD J. FERRIS, OF HARVARD, ILLINOIS, ASSIGNOR TO HUNT, HELM, FERRIS & COMPANY, OF HARVARD, ILLINOIS, A CORPORATION OF ILLINOIS.

ANIMAL PEN.

Application filed October 8, 1920. Serial No. 415,506.

To all whom it may concern:

Be it known that I, HOWARD J. FERRIS, a citizen of the United States, residing at Harvard, in the county of McHenry and State of Illinois, have invented a new and useful Improvement in Animal Pens, of which the following is a specification.

This invention relates to animal pens and is fully described in the following specification and shown in the accompanying drawing in which:

Fig. 1 is a partial elevation of a corner of a pen embodying the invention;

Fig. 2 is a partial plan of the same;

Fig. 3 is an enlarged vertical section on the line 3 of Fig. 2;

Fig. 4 is a similar section on the line 4 of Fig. 2; and,

Fig. 5 is an enlarged vertical section of the corner post on the line 5 of Fig. 2.

In the embodiment illustrated the pen consists of top and bottom rails 10 and 11 respectively which are secured to the corner post 12 by means of corner brackets 13.

Vertical tubes 14 are cut to a uniform length and secured between the top and bottom rails 10 and 11. Cup shaped members 15 are secured by means of rivets 16 on the adjacent side of the web of the channels forming the top and bottom rails 10 and 11. These members are formed to fit snugly into the ends of the tubes 14 and to prevent lateral displacement.

In some of the vertical tubes as shown in Fig. 4 a cup shaped member 15^a is used, 35 having an enlarged opening thru which passes a thimble 16^a, by means of which it is secured to one of the rails. A bolt 17 passes thru the thimble 16^a and has a nut 18 by means of which the top and bottom rails 40 10 and 11 and the tubes 14 are securely fastened together.

While I have shown and described but two embodiments of my invention it is to be understood that it is capable of many more 45 modifications. Changes, therefore, in the construction and arrangement may be made which do not depart from the spirit and scope of the appended claim in which it is my intention to claim all novelty inherent 50 in my invention as broadly as possible in view of the prior art.

What I claim as new and desire to secure by Letters Patent is:

In an animal pen, horizontal top and 55 bottom rails, vertical tubes extending therebetween and contacting said rails, cup shaped members secured to said rails and extending into said tubes to position the latter, said members being secured to said 60 rails by hollow rivets, and bolts passing thru certain of said hollow rivets and tubes to secure the whole together.

HOWARD J. FERRIS.
